UNITED STATES PATENT OFFICE

142,165

DESIGN FOR A MIRROR AND SUPPORT THEREFOR

Harry J. Feist, Fremont, Ohio, assignor to Consolite Corporation, Fremont, Ohio, a corporation of Ohio

Application February 26, 1945, Serial No. 118,214

Term of patent 7 years

(Cl. D33—9)

To all whom it may concern:

Be it known that I, Harry J. Feist, a citizen of the United States of America, residing at Fremont, Sandusky County, Ohio, have invented new, original, and ornamental Design for Mirror and Support therefor, of which the following is a specification, reference being had to the accompanying drawing, forming part thereof.

Fig. 1 is a perspective view, looking from the left, at the mirror and support therefor; and

Fig. 2 is a perspective view thereof looking from the right.

I claim:

The ornamental design for a mirror and support therefor, as shown.

HARRY J. FEIST.
